Primary Examiner — Celia Murphy*Assistant Examiner* — Clare Ann Gannon*(74) Attorney, Agent, or Firm* — Klarquist Sparkman, LLPCLAIM

I claim the ornamental design for a yoga towel/mat with pattern, as shown and described.

DESCRIPTION

FIG. 1 is a perspective view of the design, as view from the top and one side thereof;

FIG. 2 is a top plan view thereof;

FIG. 3 is a right side elevation view thereof, wherein the left side elevation view is a mirror image of the right side elevation view;

FIG. 4 is a front side elevation view thereof, wherein the rear side elevation view is a mirror image of the front side elevation view; and,

FIG. 5 is a fragmentary enlarged front side elevation view of the portion of the design identified in FIG. 4 by the circle with arrows and the reference numeral 5.
